CLAIM

The ornamental design for a ladder with hook as shown and described.

DESCRIPTION

FIG. 1 is a front elevational view of a ladder with hook showing my new design;

FIG. 2 is a rear elevational view thereof;

FIG. 3 is a left side elevational view thereof;

FIG. 4 is a right side elevational view thereof;

FIG. 5 is a perspective view thereof;

FIG. 6 is a second perspective view thereof;

FIG. 7 is a third perspective view thereof;

FIG. 8 is an enlarged view of portion 8 shown in FIG. 1;

FIG. 9 is an enlarged view of portion 9 shown in FIG. 2;

FIG. 10 is an enlarged view of portion 10 shown in FIG. 3;

FIG. 11 is an enlarged view of portion 11 shown in FIG. 4;

FIG. 12 is an enlarged view of portion 12 shown in FIG. 5;

FIG. 13 is an enlarged view of portion 13 shown in FIG. 6; and,

FIG. 14 is an enlarged view of portion 14 shown in FIG. 7.

The dash-dot broken lines show boundaries and lead lines of enlarged portions and form no part of the claimed design.
